COFFEE TABLE

Robert E. Bowers, 4875 E. Home,
Fresno, Calif. 93702

Filed Dec. 13, 1965, Ser. No. 160

Term of patent 14 years

(Cl. D33—14)

FIG. 1.

FIG. 2.

FIG. 3.

FIG. 4.

FIG. 1 is a top plan view of the coffee table showing my new design.

FIG. 2 is a side elevation thereof, the opposite side of the table being identical to the side shown.

FIG. 3 is a bottom plan view thereof.

FIG. 4 is a perspective thereof.

I claim:

The ornamental design for a coffee table, as shown.
